UNITED STATES PATENT OFFICE.

FRANK NORTH CHAMBERS, OF DAVISON, MICHIGAN.

CRADLE.

1,386,236.

Specification of Letters Patent.

Patented Aug. 2, 1921.

Application filed February 27, 1919. Serial No. 279,621.

To all whom it may concern:

Be it known that I, FRANK N. CHAMBERS, a citizen of the United States, residing at Davison, in the county of Genesee and State 5 of Michigan, have invented certain new and useful Improvements in Cradles, of which the following is a specification.

This invention relates to cradles, of the swinging and bouncing type, such as are 10 commonly known as "bassinette" and an object of the invention is to provide in a cradle for infants, a basket, a support therefor, and yieldable means connecting the basket to the support to permit swinging movement 15 of the basket, and also vertical up and down movement of the basket, and to provide a foot pedal which is adapted for connection to the basket, for either swinging or bouncing the said basket.

20 A further object of the invention is to provide a cradle of this type which is attractive in appearance, comparatively simple in construction and in which the supporting structures may be disconnected or 25 knocked-down for storage or shipping.

Other objects of the invention will appear in the following detailed description taken in connection with the accompanying drawing, forming a part of this specification 30 and in which drawing:

Figure 1 is a side elevation of the improved cradle.

Fig. 2 is a vertical section through the cradle structure showing the basket in end 35 elevation.

Fig. 3 is a fragmentary horizontal section through the cradle supporting structure, and

Fig. 4 is a fragmentary vertical section 40 through the structure showing the cradle in position for bouncing by the operation of the foot treadle.

Referring more particularly to the drawings, 1 indicates the base or supporting 45 structure of the cradle as an entirety which comprises a pair of ends or cross members 2 and 3. These end or cross members 2 and 3 are provided with recesses 4 extending thereinto, intermediate their ends, from 50 their inner facing sides, the said recesses terminating short of the width of the cross pieces as clearly shown in Fig. 1 of the drawings. The recesses 4 receive therein the ends of the longitudinally extending connecting and bracing bar 5 which connect 55 the end or crossed pieces 2 and 3 and which

is in turn connected to the cross pieces by the lower ends of the standards 6 and 7. The lower ends of the standards 6 and 7 extend through suitable openings in the ends 60 of the longitudinal connecting bar 5, and through suitable openings in the centers of the cross or end members 2 and 3, as clearly shown in Fig. 1, being retained in place by suitable nuts 8. The upper end of the standards 6 and 7 are sinuously bent as shown at 8 to provide upwardly opening loops 9 which receive therein rings formed upon the upper ends of spiral springs 10. The spiral springs 10 have chains or analogous 70 flexible elements 11 connected to their lower ends, which chains or flexible elements are in turn connected to loops 12. The loops 12 are attached to the basket or retaining body 14 of the cradle structure, in such 75 manner as to prevent their pulling loose under the weight of the infant in the basket. When assembled, the container 14 is suspended intermediate the standards 6 and 7 by the downwardly converging connecting 80 elements 10 and 11 each inclined at an acute angle to the vertical, to more firmly fix the container from lateral movement with respect to the standards.

The basket or container 14 has an eye 15 85 connected to the center of the bottom thereof, to which eye a rod 16 is connected. The rod 16 is provided with hooks upon both of its ends, one to engage in the eye 15 and the other to engage through an eye in the end 90 of the rod 17 which projects longitudinally from the end of the foot pedal 18. The rod 16 extends downwardly through an opening 19 formed in the longitudinal connecting bar 5 and a wear plate 20 is attached to the upper surface of the bar 5. The rod 16 extending downwardly through the opening 19 will be prevented from swinging movement 95 upon pivotal movement of the foot pedal 18 and the pivotal movement of the foot pedal 100 100 will be transmitted to the basket or container 14 in such manner as to cause the latter to bounce or move in a substantially vertical plane. The foot pedal 18 is hingedly or pivotally connected as shown at 22 to a suitable 105 supporting rest 23. The foot pedal 18 has an eye 24 connected at its free end and extending upwardly therefrom to which a rod 25 is adapted to be connected in lieu of the rod 16, being connected to the longitudinally 110 extending rod 17. The rod 25, is also adapted for connection with the eye 15, to swing

the basket or container 14 upon pivotal movement of the foot pedal 18. This rod 25 which is shown in Figs. 1, 2 and 3 of the drawings, is bent, so as to clear the connecting bar 5 and also so as to position the point of connection between the basket and pedal in diagonal relation with respect to each other and also to position the point of connection of the rod 25 and the pedal and the 10 swinging point or pivot of the basket in diagonal relation, so that upon pivotal movement of the foot pedal 18, the basket or container 14 will be swung in a lateral manner.

15 From the foregoing description and the drawings, it will be apparent that a cradle for infants has been provided, wherein the operation of the foot pedal 18 may be utilized to either bounce the cradle or basket structure or to swing the same, depending upon the connection between the pedal and the basket or container which connection may be regulated at the desires of the user.

Changes in details may be made without 25 departing from the spirit of this invention, but;

I claim:

1. In a cradle, the combination of a supporting structure including standards and 30 a bar adjacent the lower ends of said stand-

ards for holding them in spaced apart relation, said bar provided with a verticle slot extending longitudinally of the bar, a container, means yieldably connecting said container to said standards, to permit vertical 35 bouncing or lateral swinging movement of the container, a foot pedal oscillatable below the said bar of said supporting structure, and a rod connecting said foot pedal and the lower portion of said container, said rod 40 extending through the slot of said bar and guided thereby to impart vertical bouncing movement to said container upon oscillation of said foot pedal.

2. In a cradle, the combination of a sup- 45 porting structure including standards and a spacing bar, said spacing bar having an aperture therein, a container, means yieldably supporting said container from said supporting structure, a foot pedal mounted 50 below the bar of said supporting structure, and a rod connecting the free end of said foot pedal and extending upwardly through the aperture in said bar, and operatively connected to said container, whereby upon 55 oscillation of said foot pedal, said rod will be guided within the aperture of said bar for imparting a bouncing movement to said container.

FRANK NORTH CHAMBERS.
